UNITED STATES PATENT OFFICE.

LISLE C. WILLIAMS, OF HELENA, MONTANA.

RIFLE-CLEANING CARTRIDGE.

1,231,227.

Specification of Letters Patent. Patented June 26, 1917.

Application filed November 20, 1916. Serial No. 132,381.

To all whom it may concern:

Be it known that I, LISLE C. WILLIAMS, a citizen of the United States, residing at Helena, in the county of Lewis and Clark, 5 State of Montana, have invented certain new and useful Improvements in Rifle-Cleaning Cartridges; and I do hereby declare the following to be a full, clear, and exact description of the invention, such as 10 will enable others skilled in the art to which it appertains to make and use the same.

This invention relates to improvements in cleaning and lubricating devices, and particularly to devices used for cleaning the 15 barrels of rifles and guns.

One object of the present invention is to provide a simple and novel device which is arranged to be fired through the barrel of the rifle, in the same manner as the ordinary 20 bullet, but with the effect that the interior of the barrel will be effectively cleaned by the passage of the projectile therethrough.

Another object is to provide a device of this character whereby the cleaning material carried by the projectile will be held in 25 proper position in operation, but will effectively expand to engage the interior surface of the barrel.

Other objects and advantages will be apparent from the following description when taken in connection with the accompanying drawing.

In the drawing:

Figure 1 is an elevation of a cartridge 35 made in accordance with my invention.

Fig. 2 is a longitudinal sectional view taken on the line 2—2 of Fig. 1.

Fig. 3 is a transverse sectional view taken on the line 3—3 of Fig. 2.

Fig. 4 is perspective view of the projectile 40 removed from the shell.

Referring particularly to the accompanying drawing 10 represents a shell which is formed of any suitable material, but preferably metal, and of a shape similar to that used in the ordinary metallic cartridge shells now used. In the rear end, or closed end of

the shell, there is disposed a charge of explosive material 11, which is adapted to force the projectile 12 from the shell. 50 Directly in front of the charge of explosive, is disposed a lead or other metal plug 13. Embedded in the center of this plug is the enlarged end 14' of a stem 14, which extends longitudinally through the center of the 55 shell. The other, or outer enlarged end 14'' of this stem is embedded in the center of the projectile 12. The projectile 12 is secured in the outer, or open end of the shell in the usual manner, and filling the space, in the 60 shell between the projectile and the plug, and surrounding the stem which connects them, is a mass of cleaning material 15. This material is preferably of cotton waste, felt, or other similar material which can be packed 65 in the shell to a highly compressed degree, so that it will freely expand within the barrel of the rifle or gun, when the projectile leaves the shell and passes through the barrel. The cleaning material will thus frictionally bear on the interior face of the barrel 70 and remove the carbon or other matter which might collect on the said surface or within the rifling of the barrel.

What is claimed is:

The combination with a cartridge shell, of a gun barrel cleaning projectile located in the shell and including a tapering outer member, an inner disk member disposed in spaced relation to the rear of the tapering 80 member and arranged to receive the explosion of the charge of powder in the shell, a connecting and spacing stem having enlarged ends embedded centrally in the tapering member and in the disk member, and an 85 expansible fabric disposed around the stem and between the tapering member and the disk member.

In testimony whereof, I affix my signature, in the presence of two witnesses.

LISLE C. WILLIAMS.
